APPARATUS FOR CASTING METAL ARTICLES

Julius Aderer, New York, N. Y.; Edwin Aderer, New York, N. Y., Walter Aderer, Cleveland, Ohio, and Fritz Weckman, Larchmont, N. Y., executors of said Julius Aderer, deceased, as signors to Julius Aderer, Inc., New York, N. Y., a corporation of New York

Application May 27, 1939, Serial No. 276,123

1 Claim. (Cl. 22—65)

The invention relates to apparatus and method for casting articles such as dental plates, dentures, and the like from the customary molten metals or alloys of which such articles are constituted.

The object of the invention is to supply dental laboratories with means which will assure that the molten metal, at the time that it is forced into the mold, is in the proper condition with respect to fluidity and temperature. Thus, if the molten alloy which is about to enter the mold cavity is not hot enough to enable it to reach completely the outermost parts of the mold cavity before solidifying, the casting will be a failure, and the same thing is true if the alloy is not sufficiently free-flowing to fill the mold completely before solidification. There is for each alloy a limited temperature which represents the minimum temperature at which the mold cavity will be properly filled. It is exceedingly difficult, if not impossible, for the ordinary dental technician to determine whether the proper casting temperature has been reached in the case of whatever alloy may be used for any particular casting. The usual procedure thus far has been to direct a blow pipe discharging an ignited mixture of gas and air under pressure, or, in the case of the higher melting alloys, an oxy-hydrogen flame directly upon the metal to be melted. In other cases the metal is melted in a crucible through the walls of which the heat from melting the alloy is made effective. In all such instances the operator is compelled to estimate that the metal is in a proper condition to be forced into the mold. That failures frequently occur in such a process is obvious and it is the object of the present invention to provide reliable means by which without guess-work or estimation the alloy will be brought to the proper condition for delivery to the mold when and not until when the molten alloy has acquired the requisite temperature and fluidity.

The invention is illustrated in the accompanying drawing in which Fig. 1 is a section of a mold associated with a crucible embodying my invention. Fig. 2 is an enlarged fragmentary sectional view of the outlet portion of the crucible of Fig. 1 with indications of the dimensions of the orifice noted thereon. Fig. 3 is a top view of a different form of crucible embodying the invention. Fig. 4 is a section on line 4—4 of Fig. 3. Fig. 5 is a view of the crucible of Fig. 3 looking at the exit end thereof. Fig. 6 is a perspective view of a centrifugal type of casting machine suitable for use in conjunction with crucibles

such as are indicated in Figs. 3 to 7, and Fig. 7 is a view partially in section of still another form of crucible.

In Fig. 1 the mold block 1, customarily termed "the investment" is generally a composition of plaster of Paris and powdered silicon within which is embedded a wax model of the casting to be made and small wax rods to connect the wax model with the pocket 2 of the investment. The wax is then completely melted away, which leaves the mold cavity 3 and the sprues or passages 4 open and ready to receive the molten metal. The block 1 is usually held within an iron ring and in ordinary practice is generally associated with an appropriate casting machine 15 which may be of any ordinary type such as a rotating centrifugal or pressure or suction device. The block 1 is generally heated to a temperature of about 1200° F. A crucible is then associated with the mold or vice versa, whereupon alloy material is placed into the cavity of the crucible and melted by the application of heat. When the operator estimates that the melting has gone far enough, he lets the molten alloy flow into the mold.

In contrast with this ordinary procedure I place a crucible 5 upon the investment 1 (when proceeding in accordance with the method illustrated in Fig. 1), said crucible having a melting pocket 6 and an exit orifice 7, the orifice having approximately the dimensions of about 4 mm. diameter at the top, about 3 mm. diameter at the bottom, and a depth of about 4 mm. The crucible is made of graphite, carbon, or other smooth refractory material such as magnesia. The convex cavity 6 is used for conducting the melting process and the dimensions of the small exit orifice are such that the molten metal will not run out until it has arrived at a temperature and degree of fluidity above the minimum, irrespective of what may be the nature or the melting point of the alloy ingredients. Thus a crucible such as described will serve for a molten alloy whose casting temperature is 1600° F. as well as for an alloy whose casting temperature is 2300° F. The alloy material usually consists of several ingredients including gold or precious metals, platinum, palladium, copper, silver, etc. The casting itself is usually not heavy so that the quantities to be melted in the crucible 5 usually vary from a very little above 5 to perhaps 40 pennyweights. The convex cavity 6 of the crucible 5 is about 2½ inches in diameter and about ¾ of an inch high above the aperture 7. The alloy to be molten is usually mixed with appropriate quantities of

powdered charcoal which acts as a deoxidizer, borax, which prevents oxidation and forms minute film coatings on the particles, and boracic acid which serves a function similar to that of borax but reduces stickiness. The metal particles in association with such fluxes are now melted by the use of a blow pipe feeding an ignited mixture of air and gas under pressure, or, if the alloy has a high melting point, by the use of an oxy-hydrogen flame. Electricity can also be used as a heating medium. In any event, the heat treatment is continued after the metal is in a molten condition so that its temperatures will continue to be elevated. At a given moment the molten metal automatically runs freely through the orifice 7, whereupon it is forced into the sprues 4 and into the mold cavity 3 by any suitable available means such as gravity, centrifugal force, pressure, or in some cases suction. At the ordinary melting point of the alloy it will not flow through the aperture 7. A cohesive tendency of the molten metal must apparently be overcome and the addition of more heat accomplishes this end and simultaneously provides the necessary surplus heat to prevent failure of the molten metal to fill the mold cavity completely. Some of the alloys should have a temperature of at least 1600° F. before being permitted to enter the mold and the described crucible will automatically retain the metal within its own confines until it has at least a temperature of 1600° F. The temperature may be somewhat higher since limited increase of temperature does not do any harm, but it should not be lower and this is the effect which is guaranteed by the construction of the crucible 5. Other alloys require a temperature of 2300° F. and the same mold in that case holds the material in the crucible until it has a temperature of at least 2300° F., whereupon the molten metal will flow through the exit orifice of the crucible. In the case of the alloys used for dental castings where it is necessary to arrive at a specific minimum temperature with reference to each alloy, this result is brought about by the use of the new crucible with every type and variety of such alloys, or whatever may be the appropriate minimum temperature for such alloys.

The passage of the molten alloy through the aperture 7, when it does pass through, is relatively fast, with the result that the cataract maintains the walls of the aperture clean and unobstructed. The cavity 6 occasionally shows traces of the fluxing material which can be cleaned away, but the aperture 7, speaking generally, is not thus affected.

Turning next to the crucible shown in Figs. 3 to 5, that crucible 5a is constituted of a single block of refractory material having an open top, a partially over-hanging section 8, a cavity 6a, a projecting portion 9 open at 10 (Fig. 5), the lower portion of the opening 10 being above that portion of the cavity 6a indicated at 11 (Fig. 4) in which the molten metal accumulates. A duct 12 having an opening 13 through its top wall communicates with the lower portions of the molten metal in the crucible.

This crucible of Figs. 3 to 5 is adapted for connection with the mold 1 illustrated in Fig. 6, the projecting portion 9 being closely associated with the mold-admission port 2 of Fig. 6. When the metal is liquefied in this crucible, it will at first not enter the duct 12, but when its temperature and fluidity have arrived at the proper stage, it will gradually flow into the duct 12, whereupon

the molten metal will become visible through the aperture 13. The diameter of the duct 12 is about 3½ mm. and with that diameter the molten metal does not flow out of the duct 12 even though it is sufficiently fluid to be ready for injection into the receiving orifice 2 of the mold 1. When the operator perceives, through the aperture 13, that the molten metal has flowed into duct 12, he causes the supporting mechanism 14 (Fig. 6) to spin on the axis 15 to 10 set up centrifugal motion sufficient to force the molten metal contained in the crucible into the mold 1. The centrifugal mechanism 14, 15, and including the adjustable weight 16, is of standard type and need not therefore be described in 15 greater detail except to point out that the casting or saddle 17 serves to support the crucible in proper relation to the mold 1. When centrifugal motion is thus set up, the molten metal in the crucible is initially given a movement transverse to the crucible so that the molten metal climbs up to a position along the side of the crucible which is beneath the overhang 8, said overhang insuring against lateral escape of the molten metal, whereupon the centrifugal motion 20 forces the molten metal in a direction longitudinal of the crucible and into the receiving orifice 2 of the mold 1. In this operation the molten metal which is in the duct 12 is first withdrawn therefrom due to the transverse movement of the metal in the crucible and is then ejected into the mold through the slot 10 at a level above the duct 12. The form of the crucible illustrated in Fig. 7 is adapted for the procedure in which the heat is applied through the walls of the crucible 30 rather than by a direct flame impinging against the alloy material. In the crucible 5b of Fig. 7 the alloy is molten in the cavity 6b which is in communication with the exit orifice 18 which passes through a projection 9a similar to projection 9 of Fig. 3. The orifice 18 in this case as in the case of the orifice 7 in Figs. 1 and 2 and the orifice 12 of Figs. 4 and 5 is of such small dimensions that the metal when it is converted into the molten state will not fall through the 45 same until by increased heating the temperature and fluidity of the metal have reached a stage of adequate preparation for introduction into the mold. A peep hole 13a of smaller dimensions than the orifice 18 and therefore more resistant 50 to the flow therethrough of the molten metal, at the side of the crucible connects with the passage 18. When a crucible of this type is associated with the mold shown in Fig. 6 appropriate supporting means corresponding to saddle 17 is 55 provided for it. When the metal is first melted in the crucible of Fig. 7 it does not flow into the outlet duct 18 for the reasons previously explained but as the metal increases in fluidity and temperature in the cavity 6b it begins to flow into said 60 channel. As the molten metal passes the orifice 13a it will not flow through that opening for the reasons previously explained but will become visible to the operator and the operator is thereby advised that the metal is in a condition for 65 being ejected from the crucible into the mold and the ejection of the metal from said crucible proceeds in the same manner as previously described in connection with Figs. 3 to 6 i. e., the rotational force of the centrifugal mechanism will 70 first urge the molten metal toward the side of the crucible which is opposite the peep hole 13a whereupon the metal hugging said side will be ejected from the crucible by the centrifugal force.

I claim:

A casting device comprising a melting crucible adapted to contain a charge of material to be alloyed, said crucible being provided with a passage of such limited dimensions that the metal will not flow into said passage until the temperature of the molten alloy is higher than its melting point, said crucible being additionally provided with an exit channel for the molten metal above the restricted passage, a centrifugal device for causing a propulsive discharge of the molten metal from the crucible upon acquisition

of its higher temperature into a mold, the exit orifice of said channel facing away from the axis of the centrifugal device and the side of the crucible opposite to the direction of movement of the crucible by the centrifugal device during ⁵ ejection of the molten alloy into the mold, being provided with an over-hanging top edge section to guard against escape of molten metal from that side of the crucible.
